CLAIM

We claim the ornamental design for an electronic component, as shown and described.

DESCRIPTION

FIG. 1 is a top perspective view of an electronic component in accordance with our new design;

FIG. 2 is a bottom perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof;

FIG. 8 is a bottom view thereof;

FIG. 9 is a top perspective view of an alternate electronic portion in accordance with our new design;

FIG. 10 is a bottom perspective view thereof;

FIG. 11 is a front elevation view thereof;

FIG. 12 is a rear elevation view thereof;

FIG. 13 is a right-side elevation view thereof;

FIG. 14 is a left-side elevation view thereof;

FIG. 15 is a top plan view thereof; and,

FIG. 16 is a bottom view thereof.

The broken lines in the drawings illustrate portions of the electronic component that form no part of the claimed design.

1 Claim, 8 Drawing Sheets
